DESIGN FOR A PROJECTOR

John T. Armbruster, Niagara Falls, N. Y., assignor
to Spencer Lens Company, Buffalo, N. Y., a cor-
poration of New York

Application March 10, 1942, Serial No. 106,126

Term of patent 14 years

To all whom it may concern:

Be it known that I, John T. Armbruster, a citizen of the United States of America, residing at 217 74th Street, Niagara Falls, in the county of Niagara and State of New York, have invented a new, original, and ornamental Design for a Projector, of which the following is a specification, reference being made to the accompanying drawing, forming a part thereof.

Fig. 1 is a front perspective view of a projector, showing my new design on a somewhat enlarged

scale when compared with the disclosures in Figs. 2 and 3.

Fig. 2 is a side view thereof, the opposite side being similar; and

Fig. 3 is a top view thereof.

The characteristic features of the design are shown in full lines on the drawing.

I claim:

The ornamental design for a projector, substantially as shown and described.

JOHN T. ARMBRUSTER.
